HYDRAULIC TRANSMITTER MECHANISM

Newman C. Jannsen, Seattle, Wash.

Application December 23, 1946, Serial No. 717,827

2 Claims. (Cl. 60—54.6)

1

My present invention relates to the general art of steering devices for boats, ships, and the like, and more particularly, to a hydraulic transmitter mechanism.

Ever since the decline of sailing ships, it has been customary in ships propelled other than by sail, to have the steering station removed considerably from the steering rudder and many arrangements have been provided for connecting the remote steering wheel to the rudder, so that it can properly control the course of a wheel.

In the past, ropes, chains, and rods have been the principal connecting means between the steering wheel and the rudder. All such means, however, must employ a circuitous route passing over a plurality of sheaves and, due to their length, a very appreciable amount of slack invariably occurs in the assembly. Formerly, when only rope was used, considerable difficulty was experienced with the shrinking and stretching of the rope due to changes in the humidity. This led to the adoption of chains and rods. However, such means, because of their weight, were objectionable, as the unsupported weight between sheaves tended to cause sagging in the elements, or in the actual mass, which produced slack, and made steering an arduous task.

It is the principal object of my invention, therefore, to provide means having little or no mass, and which can be adjusted so that there is no slack or lost motion between the steering wheel and the rudder post.

A further object of my invention is to provide hydraulic control means so that the movement of the steering wheel will cause a corresponding movement in the rudder post.

A further object of my present invention is to provide a steering arrangement whereby the means connecting the steering wheel and the rudder post may be in the form of a fluid-carrying tube, or tubes, so that they can be passed through any convenient part of the ship and can take a circuitous route, if necessary, and will operate effectively without the employment of straight runs of the connecting means or the resultant multiplicity of sheaves so common in every day use.

A further object of my present invention is to provide means whereby the fluid lines transmitting the intelligence from the steering wheel to the rudder post may be constantly refilled with fluid and balanced with each other so that the intelligence will be accurately transmitted.

A further object of my present invention is to provide means whereby any ratio or degree of

2

mechanical advantage can be obtained between the steering wheel and the rudder post.

Other objects and advantages of this invention will be apparent, it is believed, after a careful study of the accompanying drawings and description, or may be readily comprehended from such study.

Referring to the disclosure in the drawings:

Fig. 1 is an elevational view showing the steering wheel; its associated mechanism, the rudder post and the operating means employed for shifting its position;

Fig. 2 is a view similar in part to Fig. 1 showing a front elevation of the mechanism and the steering station, but showing the steering wheel itself removed with certain parts in dotted outline or in section;

Fig. 3 is a vertical sectional view taken with a cutting plane on line 3—3 passing through the center of Fig. 2;

Fig. 4 is a vertical sectional view of the valve means taken in a plane at right angles to the showing in Fig. 3.

Referring to the drawings, throughout which like reference characters indicate like parts, the numeral 10 designates the conventional type of steering wheel of whatever form is most desired for the installation. The steering wheel is mounted upon shaft 12, which in turn is journaled upon bearings 14 and 16. Shaft 12 is preferably provided with a positioning screw 18 in the base casting, and arranged to bear in annular groove 19 cut in shaft 12.

Secured to or formed as part of shaft 12, is the steering wheel pinion 20. Pinion 20 meshes normally with a larger gear as 22. Gear 22 in turn meshes with rack gears 24 and 25. With the gearing so arranged, it is possible to employ a small driving pinion 20, so that adequate reduction or mechanical advantage is obtained and, by the use of a larger gear 22, racks 24 and 25 may be spread apart sufficiently to provide adequate working room for the necessary associated parts.

Gear 22 is preferably disposed as an idle gear, riding upon shaft 21, which in turn is fixedly secured in place as by the lock screw 23.

Racks 24 and 25 are formed as part of or secured to pistons 30 and 32, respectively. These pistons are adapted for reciprocation within fluid cylinders 34 and 35, respectively. At their upper ends, pistons 30 and 32 are guided in the same unit which forms a bearing for the gears, as 36 and 37. It will be understood that cylinders 34 and 35 provide adequate guiding for the lower portions of these pistons.

Pistons 30 and 32 are provided at their lower ends with obturating piston cups 40, which are so arranged as to provide sealing means, and thus prevent oil or other fluid passing around the pistons and out through the packing 41 and gland 42. With the present arrangement of cups 40, very little fluid need be stopped by packing 41. Pistons 30 and 32 are provided with longitudinal bores as 44 and 45 which communicate with cylinders 34 and 35 and terminate at the upper end with stop cocks at 47 and 48.

At their lower ends, cylinders 34 and 35 are provided with their working fluid lines 50 and 51, which lead to the rudder control cylinders. Cylinders 34 and 35 are further provided with re-supply lines 53 and 54, each of which have within them a pet cock, as 56 and 57.

Lines 53 and 54 terminate in a valve means, as will be observed in Figures 2 and 3. This valving arrangement consists of the body portion 60, a valve 61, having a head portion 62, the seating spring 63 and an operating crank pin 64 which is secured to gear 22. A fluid supply line 66 supplies fluid under pressure to the valve means.

The fluid service lines 50 and 51 lead from the wheel position to the rudder actuating cylinders 70 and 71. These cylinders are pivoted, as at 73 and 74, to pivots which are secured to some fixed portion of the vessel. Attention is directed to the fact that lines 50 and 51 must be so connected to cylinders 70 and 71 that the small oscillation of the cylinders will not damage the piping. Such arrangements are normally well known to persons accustomed to this type of work where long runs of tubing can be made and no special precautions need be taken. In some instances, it is necessary to provide small coils adjacent the cylinders, or possibly in extreme cases some type of rotary transfer joints might be desirable.

Cylinders 70 and 71 are provided with fluid actuated pistons 76 and 77. These pistons are pivotably connected at 79 to the rudder actuating arm 80. This arm is in turn keyed to the rudder post 82. At this point special reference is made to Fig. 1, in which it will be observed that, as arm 80 is moved in either direction from the medial line, the rudder 83 is similarly moved.

In order to provide against lack of fluid or air pockets in the fluid line which might cause malfunctioning of my equipment, or at least might prevent the wheel from accurately registering the position of the rudder, I have provided the re-supply tank 85. This tank is normally partially filled with fluid as 86, and provision is made for an air dome as 87. The tank may be supplied with air under pressure from any convenient source, as the line carrying the valve 88. As a convenience and a check on the system, I provide the pressure gauge at 89.

Method of operation

When my equipment is set up initially for use, the entire system is filled with a suitable fluid, normally a non-compressible liquid, usually having some lubricating properties and one further that is not subject to freezing. As the system is placed in operation, it will be found that a certain amount of air will normally be trapped in cylinders 34 and 35. This can be drawn off by opening valves or pet cocks 47 and 48, allowing all the air to escape. This will be evidenced by liquid appearing at the valves. The system should now be in proper working order, and if the operator or helmsman desires to change his rudder position, he may turn the steering wheel in

either direction. This will raise one piston and lower the other, as viewed in Fig. 2, and will thus cause, in this instance shown, the fluid to be forced through tube 51 to cylinder 71, forcing piston 77 to the right as viewed in Fig. 1. At the same time that piston 77 is being forced downwardly, piston 30 is being moved upwardly, and this withdraws fluid through pipe 50 from cylinder 70, thus permitting piston 76 to be moved to the right and thus the rudder itself will move to the right as indicated; if the wheel is turned in the reverse direction, the reversal of the entire cycle as explained above will occur.

In new equipment, this operation can be carried out for a long period without any mal-functioning in the system. However, when the equipment becomes worn through use or is improperly adjusted by inexperienced persons, I find it desirable to provide automatic means for the readjustment of my system.

In order to compensate for any loss of fluid, I have provided a re-supply means, which draws fluid under pressure from tank 85. This fluid is delivered through tube 66 to the valve mechanism 60. It here fills the lower cavity 90 of the valving means and surrounds spring 63. I then provide that gear 22 be of a size so that one revolution moves racks 24 and 25 throughout their entire movement. I then position pin or crank 64 so that each time the cylinders are equi-positioned, rudder 83 is in a prolongation of the boat axis, which normally should be evidenced on the steering wheel itself, many wheels having for this purpose a marker or master spoke. In following out this principle then, each time my system passes the center line, crank pin 64 will depress valve 61, and as the head of valve 61, as 62, is smaller in diameter than the bore of chamber 90, fluid will pass around the same up the dotted-in passage-way 92 shown in Fig. 3, and out through the re-supply tubes 53 or 54, in order to resupply those cylinders as the need may be with sufficient new fluid to entirely bring them back to the normal operating position.

This same re-supply system will function to re-supply fluid that may be expelled out through pet cocks 47 or 48 in order to test for the presence of air in the entire system. It will be noted that any such unbalancing of the system, as might be occasioned by testing either or both cylinders 34 and 35, will be corrected the next time the rudder assembly passes dead center again, through the functioning of crank 64 and valve 61. I have provided shut-off cocks 56 and 57 so that if it is necessary to re-supply or service tank 85, these members may be closed and the piston will then operate without re-supply until the re-supply system has again been put into serviceable condition.

It is believed that it will be clearly apparent from the above description and disclosure in the drawings that the invention comprehends a novel construction of a hydraulic transmitter mechanism.

Having thus described my invention, I claim:

1. A hydraulic transmitter mechanism in a hydraulic steering system for ships, comprising: a pair of parallelly disposed fluid cylinders; a fluid service tube leading from each of said fluid cylinders; pistons disposed for reciprocation synchronously in opposite directions within said cylinders; a gear rack secured to each of said pistons; an idle gear disposed between and operatively engaging said gear racks; a pinion gear operatively engaging said idle gear; a manually

operated wheel adapted to turn said pinion gear; said pistons having longitudinal bores which communicate at one end with said cylinders; stop cocks on the free end of said pistons in operative connection with the other end of said longitudinal bores; a re-supply tank; a valve chamber; a valve positioned in said valve chamber with an upstanding stem and with a valve head in a horizontal position; a spring in said chamber bearing on the underside of the valve head urging it upwards; a tube leading from said re-supply tank to said chamber; said chamber having two passageways leading from above said valve head to the outside of the chamber; re-supply tubes leading from said passageways to said cylinders; a pet cock on each of said re-supply tubes; and a crank pin secured to said idle gear in position to depress said valve stem when said pistons are at an intermediate position.

2. A hydraulic transmitter mechanism in a hydraulic steering system for ships, comprising: a pair of parallelly disposed fluid cylinders; a fluid service tube leading from each of said fluid cylinders; pistons disposed for reciprocation synchronously in opposite directions within said cylinders; a gear rack secured to each of said pistons; an idle gear disposed between and operatively engaging said gear racks; a pinion gear operatively engaging said idle gear; a manually operated wheel adapted to turn said pinion gear; said pistons having longitudinal bores which

communicate at one end with said cylinders; stop cocks on the free end of said pistons in operative connection with the other end of said longitudinal bores; a re-supply tank; a valve chamber; a valve positioned in said valve chamber with an upstanding stem and with a valve head in a horizontal position; a spring in said chamber bearing on the underside of the valve head urging it upwards; a tube leading from said re-supply tank to said chamber; said chamber having two passageways leading from above said valve head to the outside of the chamber; re-supply tubes leading from said passageways to said cylinders; and means associated with said idle gear in position to depress said valve stem when said pistons are at an intermediate position.
